UNITED STATES PATENT OFFICE.

JOHN WARD WILLIAMS, OF BUFFALO, NEW YORK.

MUFFLER.

Application filed November 1, 1927. Serial No. 230,258.

This invention relates to a muffler which is more particularly intended for deadening or reducing the noise of the exhaust gases resulting from the explosion of charges of combustible fuel in gas engines, but the same is also useful for deadening or reducing the noise of other expanding fluids such as the exhaust steam from a steam engine.

It is the purpose of this invention to provide a muffler which is comparatively simple and inexpensive in construction and not liable to get out of order, which will efficiently muffle exhaust gases or the like without producing any undue back pressure and which is so constructed that the same is not likely to gather any considerable amount of soot, and whatever soot may accumulate can be readily and easily removed from the muffler when required.

20 In the accompanying drawings:—

Figure 1 is a longitudinal section of one form of muffler embodying my invention.

Figure 2 is a cross-section of the same taken on line 2—2 Fig. 1.

25 Figure 3 is a perspective view of one section of the baffle or partition which is arranged within the casing of the muffler.

Figure 4 is a longitudinal section showing another form of muffler constructed in accordance with my improvements.

30 Figure 5 is a cross-section of the same taken on the correspondingly numbered line in Fig. 4.

Figure 6 is a perspective view of one section or plate of the baffle or partition arranged within the casing of the muffler shown in Figs. 4 and 5.

Figure 7 is another modified form of my invention.

40 Figure 8 is a cross section taken on line 8—8 Fig. 7.

Similar characters of reference indicate like parts in the several figures of the drawings.

45 Referring to the construction shown in Figs. 1, 2, and 3 the numeral 10 represents generally the enclosing casing, shell or body of the muffler which is preferably iron. This casing preferably consists of two sections 11, 50 12 each of which has the form of a cone frustum, the large ends of these cones being arranged opposite each other and the small ends of these cones being provided respec-

tively with cylindrical necks 13, 14 which form an inlet, and an outlet respectively, for the exhaust gases of the engine which are to be muffled so as to render them noiseless as they escape from the engine. The opposing large ends of these conical sections which form the casing of the muffler can be connected with each other in any suitable manner but preferably by means of an annular seamed joint consisting of a laterally projecting peripheral flange 15 formed on the large end of the outlet section 12 and an inwardly opening hook 16 arranged on the large end of the inlet section 11 of the casing and receives a flange 15 of the outlet section 12, as shown in Fig. 1.

The space within the concave side of the hook 16 is larger than necessary to receive the flange 15 so as to form an inwardly opening channel or groove 17 between the flange 15 and the base of the hook 16 for a purpose which will presently appear.

Within the casing or shell of the muffler is arranged a transverse baffle, partition or wall which divides the interior of the casing into an inlet chamber 18 and an outlet chamber 19, and this baffle is provided with one or more labyrinth passages which place the inlet and outlet chambers of the casing in communication with each other so that the exhaust gases instead of passing directly from the inlet to the outlet chamber, are compelled to take a tortuous course and thereby cause the speed of the exhaust gases to be retarded slightly and at the same time silencing or muffling the noise which is produced by the gases as they escape in the form of exhaust from the engine.

In the preferred construction this baffle comprises two sheet metal plates or disks 20, 21, preferably of iron which are arranged with their inner flat sides engaging each other while their peripheral or edge portions are seated in the channel 17 formed within the seamed joint between the front and rear sections of the muffler casing so that this seamed joint not only connects the front and rear sections of the muffler casing but also secures the plates of the baffle against each other and holds the same in the proper position within the casing to form the inlet and outlet chambers therein.

105 Those parts of the plates 20 and 21 of the

baffle are so constructed that they form a tortuous path or passage for the exhaust gases from the inlet to the outlet chamber. In the preferred construction each of these plates is provided with a plurality of laterally offset hollow beads 22 each of which is formed by cutting a pair of slits at a suitable distance apart in the respective plate and then bending or bulging the intermediate portion of the plate outwardly so that each of these beads forms a channel 23 on its inner side which is open at its opposite ends, as shown at 24 whereby this channel communicates with one of the chambers within the casing.

The beads of one of the baffle plates are arranged at an angle to the beads of the other baffle plate so that the concave or channel side of each bead communicates between opposite ends thereof with the channel or concave side of a bead on the other plate of the baffle.

In the preferred construction each of the baffle plates is provided with three off-set or bulging beads which are arranged parallel with each other and the beads of one baffle plate are arranged at right angles to the beads of the other baffle plate, as shown in Figs. 1 and 2, whereby the intermediate part of the concave side of each bead of one baffle plate communicates with the concave sides of the beads of the other baffle plate between opposite ends thereof.

A plurality of tortuous or labyrinth passages are thus formed in the baffle through which the exhaust gases pass while moving from the inlet to the outlet chamber of the casing, thereby insuring elimination of the noise of the gases to a maximum extent. The formation of these tortuous passages is however such that there is a minimum tendency for the deposit of any soot of the gases in these passages, and any soot which ultimately is deposited within these passages can be very easily removed therefrom and thereby enable the muffler to be always maintained in the maximum state of efficiency.

In the operation of the muffler the gases pass from the inlet chamber into the opposite ends of the baffle channels of the respective baffle plate, thence from the inner parts of these channels to the inner parts of the channels of the other baffle plate and thence laterally outward from the ends of the channels in the last-mentioned plate into the outlet chamber, thereby cutting down if not wholly eliminating any noisy effect as the exhaust gases finally escape from the muffler through the outlet thereof.

Instead of making sections of the casing of conical form, as shown in Fig. 1, these sections may be made of hemispherical form, as shown at 25, 26 in Fig. 4, and inlet and outlet collars 27 and 28 of these chambers may also be made separate from the walls of these chambers and secured thereto by crimping,

as shown at 29 and 30 in Fig. 4, instead of being made integrally with the walls of the casing sections, as shown in Fig. 1.

For mufflers which are of large capacity it is preferable to employ a plurality of off-set or bulging beads on each of the baffle plates, as shown in Fig. 1, but when a muffler is intended for comparatively light duty or service each of the baffle plates or disks may be provided with a single off-set bead forming a channel on its concave side which communicates at its opposite ends with one of the chambers of the casing, while the intermediate or central part of this channel communicates with the central part of a corresponding channel arranged at right angles to the first-mentioned bead on the other baffle plate, as shown in Figs. 4, 5, 6.

Both forms of mufflers shown in the drawings and embodying my invention can be produced at comparatively low cost owing to the simplicity of the construction and the ease with which the several parts can be assembled. Moreover this muffler is very compact in construction and therefore especially suited for installation where a limited amount of space is available for a device of this character.

If desired my improved muffler may be organized with a plurality of baffles or partitions which embody my invention and which are mounted in a series within the casing as shown in Figs. 7 and 8 so that the products of combustion pass successively through the same. In this form of my invention three baffles are shown and the central one has its plates 20, 20 secured together and held in the casing by engaging the periphery or edge portions of these plates in a channel formed between the cooperating flange 15 and hook 16 of the seam joint between the two casing sections 31, 32 having the inlet 113 and the outlet 114 for the exhaust gases to be silenced.

The plates 120 and 220 of the front and rear baffles which are arranged in front and in rear of the central baffle have their edge portions turned to form pairs of peripheral flanges, as shown at 33, 34, the flanged part of the plates of the front baffle engaging with an inwardly facing annular shoulder 35 formed on the interior of the front casing section and the flanged part of the plates of the rear baffle engaging with an inwardly facing annular shoulder 36 formed on the interior of the rear casing section. The flanges of the front and rear baffles may be connected with the adjacent part of the casing by electric welding or any other suitable manner.

When a plurality of baffles is used the same are spaced apart lengthwise of the casing so as to form intermediate compartments or chambers 37, 38 which serve to connect the tortuous transfer passages in one baffle with those of another and thereby lengthen the

zig-zag course through which the exhaust gas must pass before escaping to the atmosphere and increasing the silencing effect on the gas accordingly, without perceptibly increasing 5 the back pressure on the out-going gases.

I claim as my invention:—

1. A muffler comprising a casing having an inlet and an outlet for the exhaust, and a baffle arranged within said casing between 10 said inlet and outlet including two transverse plates having flat sides opposing each other and edges mounted on the wall of said casing and forming inlet and outlet chambers therein, and each of said plates being provided 15 with a laterally projecting hollow bead, the bead of one plate being arranged at an angle relative to the bead of the other plate, and each bead opening at one end into one of said chambers and communicating between its 20 ends with the other chamber.

2. A muffler comprising a casing having an inlet and an outlet for the exhaust, and a baffle arranged transversely in the casing and dividing the same into an inlet chamber and 25 an outlet chamber and consisting of two plates which have flat sides engaging each

other and each of which has a plurality of hollow beads which are arranged at an angle to the beads of the other plate and each of said beads opening at its opposite ends into 30 one of said chambers and having its concave side communicating between the ends thereof with the concave sides of the beads of the other plate.

3. A muffler comprising a casing having an 35 inlet and an outlet for the exhaust, and a baffle arranged transversely in the casing and dividing the same into an inlet chamber and an outlet chamber and consisting of two plates which have flat sides engaging each 40 other and each of which has a hollow bead formed thereon by laterally deflecting a part of the plate so that the opposite ends of the bead open into one of the chambers, and the beads of both plates being arranged at an angle 45 relative to each other so that the concave sides of the beads of both plates communicate with each other between the ends thereof.

In testimony whereof I hereby affix my 50 signature.

JOHN WARD WILLIAMS.
